ELECTRIC SWITCH

Sigwart Ruppel, Berlin, Germany; Frida Strauss,
née Ruppel, heir of said Sigwart Ruppel, deceased

Application November 28, 1934, Serial No. 755,192
In Germany December 8, 1933

5 Claims. (Cl. 200—148)

My invention relates to electric circuit breakers of the fluid or gas-blast type wherein the arc is traversed by a jet of fluid, and has for its principal object the provision of an improved circuit breaker of the aforesaid type wherein the arc can be interrupted by a fluid blast at moderate pressure.

In gas blast circuit breakers involving a flow of gas under pressure, the breaker contacts are usually arranged to separate at the point of maximum blast effect. In general, the point of engagement of the contact elements is located at the narrowest cross section of the fluid path, such as the neck of a nozzle, through which the gas under pressure flows, the movable contact being actuated in a direction axial of the nozzle in the circuit opening operation. The interruption of the arc occurs, therefore, between the neck of the nozzle and the tip of the movable contact when the movable contact is withdrawn from the neck of the nozzle, so as to lengthen the arc, and is within a range where the gas flow may be comparatively weak. With this arrangement a comparatively high gas pressure is required in order to obtain reliable current interruption.

In accordance with my invention a compressed gas or gas blast circuit breaker is provided with a nozzle consisting entirely of insulating material. The stationary contact is mounted as an opposite pole in a widened or exhaust part of the aforesaid nozzle beyond the neck, and the movable contact is actuated during the opening movement through the neck and into the space beyond the neck.

With this arrangement the stationary contact is disposed as a counter-pole within the concentrated jet of compressed gas and is efficiently cooled thereby. Also, the higher pressure of the gas at that point effects rapid evacuation of the conducting gases therefrom during the expansion. The fresh gas following with considerable pressure maintains the region at the counter-pole comparatively free of impure gas particles. As contrasted with prior types of gas blast breakers, the narrow neck of the nozzle need not be considered as a possible base for the arc since the nozzle consists entirely of suitable insulating material and since no parts of the stationary contact are located within the neck of the nozzle.

It is preferable to design the stationary contact as a counter-pole, both as regards position and shape, in such a manner that no eddies will occur in the vicinity thereof and so that

the base of the arc can travel in accordance with the blast effect. To this end contacts in the shape of pipes and rods are suitable, the axis of which is in the direction of the gas blast. However, supporting walls and ribs, having the well-known "tear drop" cross section, disposed at right angles to the direction of the blast can be used as counter-poles. The effect is particularly favorable if a widened space is behind the counter-electrodes in the direction of the blast so that removal of the ionized gas particles from the counter-electrodes is insured.

Owing to the fact that the stationary contact serving as counter electrode is arranged in the widened portion of the nozzle, the position of the arc is determined in a definite manner or in a definite zone. The base point of the arc travelling on the counter poles and the arc itself are cooled by these counter-electrodes, so that too hot gases or the arc itself cannot get into the muffling device. Thus, it is possible, to bring the mufflers closer to the switch chamber. The counter electrodes may be united with the muffler so that the switch is considerably smaller and of lighter weight.

The switch chamber or the exhaust discharge space may be of various shapes (for instance instead of circular oval up to a narrow rectangle or of any other shape; the counter electrodes have to be shaped in accordance with the shape of the switch chamber.

Any suitable gases may be used for blowing, i. e. gases with additions, steam or the like. The gases may be supplied from separate places of production, from reservoirs, bottles or the like; they may be driven into the switch chambers whilst the same is moving or they may be produced by the effect of the arc or of the current.

Some of the possible embodiments of the invention will be hereinafter described with reference to the accompanying drawing in which:

Fig. 1 shows in vertical section partly in elevation a switch according to the invention.

Fig. 2 shows a modified contact arrangement.

Fig. 3 shows a third form of the contact arrangement.

Fig. 4 is a vertical section through Fig. 3.

Fig. 5 is a horizontal section through Fig. 4.

Fig. 6 shows a further form of contact arrangement.

The movable contact 1 shown in Fig. 1 is tubular, 2 designates the stationary contact, 3 the insulating switch casing, 4, 5 the terminals, 6 the admission of compressed air or gas, 7 the actuating switch piston, 8 the muffling device or damper.

The insulating casing 3 is nozzle-shaped at the switch point. The movable contact extends through the narrowest point 3' of the nozzle. The stationary contact 2, carried by ribs 9, is in the widened or exhaust portion of the nozzle so that it acts as counter electrode and the base point of the arc in the widened portion of the nozzle can settle on this counter electrode. The ribs carrying the counter electrode serve at the same time as terminal conductor.

The current in the switched in state of terminal 5 flows through the tubular contact 1, the counter electrode 2 and the ribs 9 to the terminal 4. The counter electrode 2 is preferably an 15 elongated body of oval longitudinal section so that its outer surface extends essentially in stream line shape, and the formation of eddies is avoided. The contact is established in that the top 20 end of the tubular contact 1, which transmits the current to the counter electrode 2 is pressed strongly against the counter electrode 2 either by the action of springs or by its own resiliency obtained for instance by slits. The tube 2, forming the movable contact, has apertures 10 at suitable points, through which the blowing air flows 25 through the interior of the tube to the contacts. The arrangement may be such that in the switched in state no gas or only very little gas flows out from the space 11.

30 The switching-out is effected when the air admission 6 is connected with a container of compressed air. The compressed air flows then into the space above the piston 7 so that the movable contact descends through the neck 3'. The compressed air blows strongly through the neck 3' on to the contacts so that by the blowing effect and by the cooling effect of the flowing pressure gas the arc is extinguished by moderate gas pressure in or at the restricted portion 3'. The switching 35 in is effected by admitting compressed air into the space below the piston. In this arrangement not only the switch chamber but also the nozzle and the damper may be made of insulating material. The whole switch may also be easily 40 cased and insulated.

In Fig. 2 the stationary contact consists of a tube 12. The construction shown in Fig. 2 differs from that shown in Fig. 1 further in that there are no holes in the movable contact 1 so that, in open circuit state, the gas admission takes place directly from the switch chamber 11 through the narrowest point of the nozzle. The tube 12 may evidently be telescoped over instead of in the movable contact 1, this modification 50 altering not the character of the construction.

55 For reducing the friction of the gas the ribs 9 may be of drop-shaped cross section shaped according to the stream lines.

In the form of construction illustrated in Figs. 60 3 to 5 the ribs 9, preferably of drop-shaped cross section, form the stationary contact. The top 65 end of the movable contact 13 is in the form of a pin with spherical point. This point, especially its upper portion, is preferably made of material not easily evaporative, for instance tungsten. The counter electrodes or portions of the same may also be of tungsten.

In Fig. 6 the counter electrode consists of two 70 plate-shaped bodies 14, which transmit the contact pressure, by separate springs and by other suitable means, upon the switch blade. The nozzle of the casing 3 and the space 11 may be adapted to the shape of the switch blade and of the counter electrodes 14. The nozzle will then 75 be preferably of oval or rectangular shape, its

dimensions corresponding to the shape of the switch blade.

It should be understood that my invention is not limited to specific details of construction and arrangement thereof herein illustrated, and that 5 changes and modifications may occur to one skilled in the art without departing from the spirit of my invention.

I claim:—

1. A gas blast circuit breaker comprising a nozzle 10 consisting of insulating material, a stationary contact mounted in the exhaust part and beyond the neck and along the longitudinal axis of the nozzle, a coacting movable contact reciprocally operable through said neck and into the space 15 at the opposite side thereof, said neck being restricted with respect to said movable contact, and means for directing gas under pressure through said nozzle in a direction counter to circuit opening movement of said movable contact to extinguish the arc at said neck.

2. A gas blast circuit breaker comprising a nozzle consisting of insulating material, a stationary contact disposed in a widened diverging part beyond the neck and along the longitudinal 25 axis of said nozzle, said contact presenting an inappreciable resistance to gas exhausting from said neck, a coacting movable rod contact reciprocally operable through said neck and into the space at the opposite side thereof, said movable 30 contact having a comparatively close fit within said neck, and means for directing a gas under pressure upon opening of the circuit through said nozzle towards said stationary contact for traversing the arc at said neck, said gas freely 35 exhausting through said diverging part without restriction to a low pressure area.

3. An electric gas-blast switch provided with a nozzle of insulating material comprising a constriction and a gradually widening portion adjoining the constriction on one side, a chamber for gas under pressure adjoining the nozzle on the other side, a fixed contact on the side of the constriction remote from the chamber, said fixed contact being located along the longitudinal 40 axis of said nozzle and in an unobstructed position with respect to gas flow in said widening portion, and a movable contact which in the closed condition of the switch extends through the constriction but which when the switch is 45 opened is moved away from the fixed contact in a direction opposite to an unrestricted flow of gas through the nozzle from the chamber, and into the chamber so as to draw the arc which is produced on separation of the contacts from the 50 widened portion of the nozzle through an arc-extinguishing blast at said constriction and into the chamber.

4. A gas-blast circuit breaker comprising a nozzle of insulating material having a constriction 60 and a gradually widening portion adjoining the constriction on one side, a source of gas pressure adjoining the nozzle at the other side for causing a gas blast through said nozzle, a fixed contact mounted within said widened portion 65 in an unobstructing position and spaced from said constriction, metallic rib members extending transversely of said nozzle for supporting said fixed contact, said rib members and fixed contact being generally of stream-line configuration so 70 as to have minimum resistance to gas flow through said nozzle, and a movable rod contact reciprocally operable through said constriction to engage said fixed contact, circuit-opening movement of said rod contact being in a direction 75

counter to the movement of gas from said source through said constriction toward said fixed contact so that the arc formed between said contacts upon opening of the circuit is subject to a high 5 velocity gas blast within said constriction.

5. A gas blast circuit breaker comprising an insulating nozzle, an electrode connected to one terminal of the circuit arranged to be disposed at the exhaust part and beyond the neck of said 10 nozzle, a coacting movable electrode connected to

the other terminal of the circuit reciprocally operable through said neck and into the space at the opposite side thereof to engage said first-named electrode, said neck being restricted with respect to said movable electrode, and means for directing gas under pressure through said nozzle in a direction counter to the circuit opening movement of said movable electrode to extinguish the arc substantially at said neck.
